ELECTRICAL HEATING MEANS

Henri George, Paris, and Gaston Delpech, Clamart, France, assignors to Société Anonyme des Manufactures des Glaces & Produits Chimiques de Saint-Gobain, Chauny & Cirey, Paris, France

Original application January 27, 1934, Serial No. 708,618. Divided and this application May 16, 1936, Serial No. 80,052. In France January 30, 1933

3 Claims. (Cl. 13—21)

This invention relates to heating means, and relates more particularly to electrical furnaces for heating, fusing and/or casting articles made of substances having a high melting point.

5 The present application is a division of our copending patent application relating to "Heating means", Serial No. 708,618, filed January 27, 1934, and is particularly concerned with the type of furnaces used for liquid fusion.

10 In our copending patent application relating to "Electrical heating", Serial No. 648,996, filed December 27, 1932, an electrical furnace is described which comprises a heating element consisting of a carbon rod and surrounded by a container which is situated within the zone of heat radiated by the heating element and which is movable with respect to this element. A gaseous medium may be introduced into the furnace and allowed to flow between the heating element and 20 the walls of the container.

An object of the present invention is to provide certain improvements in furnaces of this type to increase their output and their efficiency.

In order to increase the output of the furnaces 25 it is necessary to have the successive operations of melting in said furnaces following each other within a time as short as possible and in order to increase the efficiency of the furnaces. The losses of heat between two successive operations 30 must be reduced as much as possible.

Consequently an object of the present invention is to facilitate the insertion of the heating element into a rotatable furnace and the removal of the heating rod therefrom and to shorten as much 35 as possible the time necessary for these operations.

The heating element may comprise a single heating rod or several rods when a polyphase current is to be used.

40 The insertion and the removal of the heating element are rendered easy by connecting one of its ends to a movable organ of the furnace.

The other end of the heating element may be supported by another organ and in this case, 45 resilient means are used to press said organ against the end of the heating element in order to maintain a steady contact between the terminals and the heating element at both ends of said element, in spite of the movements or expansion 50 of the various parts of the furnace in the course of the heating or fusing process.

Another object of the invention is to provide for 55 an air-tight connection between the terminals and the rotatable parts of the furnace, when it is necessary to have the fusing zones of furnaces devoid of contact with the surrounding atmosphere, the furnace being given an oscillating motion instead of a rotating one.

The above and other objects of the present invention may be realized through the provision 60

of an electrical furnace or furnaces which comprise a heating rod having one end which is firmly connected to a block which may consist of one or several elements. The block is supported in such manner that the height at which the heating rod is maintained may be conveniently adjusted. The block is preferably mounted upon a carriage which is movable in a direction parallel to the axis of the container which encloses the heating rod and which carries the material to be treated. If the heating rod has a small or medium sized diameter, it is advisable to provide screw threads upon one end of the heating rod and to screw that end into the supporting block. The opposite end of the heating rod may lie freely upon a second block which is located at the opposite end of the container. If the heating element is to be heated by a polyphase electrical current, it should consist of several rods, equal in number to the number of phases of the electrical current; one of these rods may be provided with screw threads on both sides. One end of the last-mentioned heating rod may be screwed into the supporting block while the other end may be screwed into a connecting member. The other heating rods of the same heating element may be freely supported by the supporting block and the connecting member.

The relative position of the heating element in relation to the rotatable container may be adjusted by adjustment of the means supporting the heating element, by adjustment of both the means supporting the heating element and the means supporting the container, or solely by adjustment of the position of the container. The block carrying a heating element may be pivotally mounted upon a chariot so that when the heating element is removed from the furnace the heating element may be moved from a horizontal to a vertical position and covered by a protective cover. The terminals connected to a source of electrical energy and supplying an electrical current to the heating element may be carried by the block mounted upon a carriage and/or by the block situated opposite the first-mentioned block.

If two blocks are used, that block which freely supports the non-threaded end of the heating rod may be made movable, such movement being limited by resilient means.

The invention will appear more clearly from 50 the following detailed description, when taken in connection with the accompanying drawings showing preferred embodiments of the inventive idea.

In the drawings:

Figure 1 shows a furnace having an hermetically closed fusing zone in axial section and partly in side elevation;

Figure 2 is a section along the line 2—2 of Figure 1;

Figure 3 is a section along the line 3—3 of Figure 1;

Figure 4 shows on a larger scale and in vertical axial section a part of the furnace illustrated in Figure 1;

Figure 5 is a section along the line 5—5 of Figure 4;

Figure 6 shows another part of the furnace illustrated in Figure 1 on a larger scale and in vertical axial section;

Figure 7 is a section along the line 7—7 of Figure 6;

Figure 8 is a section along the line 8—8 of Figure 6.

The furnace illustrated in the drawings comprises a heating rod or electrical resistance 150, the end 151 of which is provided with screw threads, as shown in Figure 4. The opposite end 152 of the resistance 150 is conical in shape, as shown in Figure 6.

The end 151 of the resistance 150 is screwed into a threaded bore hole 153 formed in a support 154, which consists of amorphous carbon (Figure 4). The opposite end of the resistance 150 is supported in a cavity formed in a block 155, which is also made of amorphous carbon (Figure 6).

A part of the block 154 is slightly conical in shape and is carried by a sleeve 156. The block 155 is supported by a similar sleeve 157. Both sleeves are conductors of electricity. A metallic casing 158 surrounds on three sides the block 156 and carries a metallic terminal 159, which may be connected to any suitable source of electrical energy not shown in the drawings.

As shown in Figure 6, a metallic casing 160 surrounds the sleeve 157 and is connected with one of the ends of an elongated tube 161. The tube 161, which is made of a conducting material carries at its opposite end a plate 162, which is firmly connected with another terminal 163.

A water jacket 164 (Figure 4) surrounds the casing 158 and carries two pipes 165 and 166, one of which serves as an inlet for the water. The water circulates between the casing 158 and the walls of the jacket 164 and cools the walls of the casing 158.

A sealing ring 167 made of insulating material is situated between the sleeve 158 and a metallic cover 168.

As shown more clearly in Figure 1 of the drawings, the main container of the furnace consists of a cylindrical body 169, which surrounds a layer 170 consisting of a heat insulating material. A lining 171, which is made of a refractory material surrounds the resistance 150 and is situated between this resistance and the insulating layer 170. The conical end cover 168 is rigidly connected with the cylindrical casing 169 by rivets or other suitable means.

A jacket 172 shown in Figure 6 is carried by the metallic casing 160 and is connected with two pipes 173 and 174, which project into the interior of the tube 161 and which pass through suitable openings formed in the plate 162. The pipes 173 and 174 are used for the circulation of a cooling medium such as water, used for cooling the metallic casing 160.

As shown more clearly in Figure 1, the cylindrical casing 169 is rigidly connected with a metallic end cover 175. A hollow casing 176, which is preferably made of sheet metal surrounds the water jacket 172. A frictional sealing ring 177 (Figures 1 and 6) made of an insulating material is interposed between the casing 176 and the end cover 175. The casing 176 is carried by a support

243 and carries a tubular sleeve or guiding member 178 which is provided with flanges 179, rigidly connected with the casing 176.

Due to this arrangement, the resistance 150 and its ends are movable to a certain extent within the casing 169 in the direction of its longitudinal axis. This axial movement is possible because the tube 161 is movable with respect to the sleeve 178.

The jacket 164 connected with the metallic casing 158 is movable along with the block 154, the resistance 150, the block 155, the sleeve 157 (Figure 6), the casing 160 and the tube 161.

The furnace is provided with resilient means for maintaining the proper contact between the end 152 of the resistance 150 and the block 155. These means comprise a bolt 180, one end of which is rigidly connected with the casing 176. The bolt 180 has screw threads 181 and carries a winged nut 182 as well as a washer 183.

A coiled spring 184 surrounds the bolt 180 and is in contact at one of its ends with the washer 183. The opposite end of the spring presses against the bifurcated end 185 of a lever 186 (Figure 8). The lever 186 is carried at its lower end by a hook 187, the opposite end of which is rigidly connected with the casing 176. The middle 188 of the lever 186 is somewhat bent and surrounds an insulating rod 189, which is firmly attached to the tube 161 and which passes through a longitudinal slit 190 formed in the sleeve 178.

As shown in Figure 8, a similar lever 191 is situated at the opposite side of the sleeve 178 and is carried by a hook 192, which is rigidly connected with the casing 176. The bifurcated end 193 of the lever 191 surrounds a bolt 194, which is also carried by the casing 176. The bolt 194 is also provided with a coiled spring, which is not shown in the drawings.

Due to the provision of the springs 184, the levers 186 and 191 maintain the tube 161 in the position shown in Figure 6. Since the tube 161 is connected with the end 152 of the heating rod 150 by the casing 160, the sleeve 157 and the block 155, the resistance 150 will be always maintained in close contact with the block 155. Otherwise, slight movements or contractions of the resistance 150 or the block 155 might cause an interruption of the electrical current between the resistance 150 and the block 155.

The cylindrical casing 169 is rigidly connected with two rings 195 and 196, which are in contact with rollers 197, 198, and 199 (Figures 1 and 2). The roller 197 is pivotally mounted in a support 200, while the roller 198 is pivotally mounted in a support 201. The roller 199 is carried by the support 202. The fourth roller and its support are not shown in the drawings. The support 200 is carried by the foundation 203, while the supports 201 and 202 are carried by the foundation 204.

The cylindrical casing 169 is rigidly connected with an annular gear 205, which meshes with a pinion 206 rigidly connected with a gear wheel 207 and rotatably mounted in the support 203. The gear wheel 207 meshes with a gear 208, which is driven by a motor 209 resting upon the support 210. The motor is provided with a switch 211, which may be used for reversing at periodic intervals the direction of rotation of the motor and thus reversing the direction of rotation of the casing 169. The switch 211 is also used for varying the speed of rotation of the motor 209.

As shown in Figures 1 and 3, the jacket 164, 75

which surrounds the casing 158 is carried by a frame 212 by means of members 213 and 214. The frame 212 is slideable in the vertical direction in two guide members 215 and 216, which are rigidly connected with and supported by a carriage 217.

The frame 212 rests upon cams 218 and 219, which are keyed upon an axle 220, rotatably mounted in the guides 215 and 216. A wheel 221 is also keyed upon the shaft 220 and is provided with a handle 222, which is used for rotating the cams 218 and 219. The carriage 216 is mounted on wheels 223 and 224 which are movable along rails 225 and 226.

15 The cams 218 and 219 are operated and the carriage 217 is moved along the rails 225 and 226, when it is necessary to take the heating element 150 out of the furnace.

In operation, the terminals 159 and 163 are connected to a source of electrical energy, which is not shown in the drawings. Then a current will flow through the terminal 159, the block 154, the resistance 150, the block 155, and tube 161 and the terminal 163.

25 When the motor 209 is started, it will revolve the casing 169 through the medium of the gear wheels 208, 207, 206, and 205. The switch 211 is used to change the speed of rotation of the casing 169 and to reverse the direction of its 30 rotation.

The material to be treated is first inserted into the furnace either through one of the axial openings or through a door formed in the container 169 and not shown in the drawings. Then the 35 heating rod 150 and the other parts of the furnace are assembled in their proper positions. Then the motor 209 is switched on, causing a rotation of the furnace. Finally, the electric current is switched on and the heat radiated by the 40 heating rod 150 causes the fusion of the material. After the fusing process has been completed the electrical current is switched off and the liquid material is removed from the interior of the container 169 through an opening not shown in the 45 drawings.

By the described construction the insertion of the heating elements into the furnace and the removal of such heating elements from the furnace is made much more rapid than in constructions 50 known in prior art. This is an important advantage, since it reduces the heat losses of electrical furnaces which consume a large amount of electrical energy, and which operate at very high temperatures.

55 Furthermore, in accordance with the described construction, the block carrying the heating element is situated within the opening serving as a charge opening for the insertion of the material to be treated. The quick removal and insertion 60 of said block makes it possible to fill the container with the material to be treated within a comparatively short time.

In certain instances the heating element and the two blocks supporting the same may be firmly connected with the container. In such instances it is advisable instead of completely rotating the container to cause it to carry out an oscillating movement about its central axis.

What is claimed is:—

70 1. In combination, a rotatable container, a heating rod within said container, said rod having a threaded end portion, means firmly engaging said threaded end portion to support one end

of said rod within said container, said means extending through an opening formed in said container and constituting a closure for said opening, a terminal adapted to be connected to a source of electrical energy and connected with 5 said means, horizontally movable means connected with the first-mentioned means for supporting the same, means connected with the second-mentioned means for adjusting the vertical position of the second-mentioned means relatively 10 to said container, means freely supporting the other end of said rod within said container, another terminal adapted to be connected to the source of electrical energy and connected with the fourth-mentioned means, means rotatable along 15 with said container and supporting the fourth-mentioned means, the fifth-mentioned means being movable relatively to the fourth-mentioned means, and resilient means carried by the fifth-mentioned means and pressing the fourth-men- 20 tioned means against said other end of the heating rod.

2. In combination, a rotatable horizontally disposed container, a single heating rod within said container, a block extending through a central 25 opening formed in said container and constituting a closure for said opening, said rod having a threaded end portion which is screwed into a threaded opening formed in said block, a terminal adapted to be connected to a source of 30 electrical energy, means electrically connecting said terminal with said block, horizontally movable means connected with the first-mentioned means for supporting said block, means connected with the second-mentioned means for 35 adjusting the vertical position of the second-mentioned means relatively to said container, means freely supporting the other end of said rod within said container, another terminal adapted to be connected to the source of electrical energy and 40 connected with the fourth-mentioned means, means rotatable along with said container and supporting the fourth-mentioned means, the fifth-mentioned means being movable relatively to the fourth-mentioned means, and resilient means 45 carried by the fifth-mentioned means and pressing the fourth-mentioned means against said other end of the heating rod.

3. In combination, a rotatable horizontally disposed container, a heating rod within said container, said rod having a threaded end portion, means firmly engaging said threaded end portion to support one end of said rod within said container, said means extending through an opening formed in said container and constituting a 50 closure for said opening, a terminal adapted to be connected to a source of electrical energy and connected with said means, a carriage supporting said means, means for adjusting the height of said carriage, means freely supporting the other 55 end of said rod within said container, another terminal adapted to be connected to the source of electrical energy and connected with the third-mentioned means, means rotatable along with said container and supporting the third-mentioned 60 means, the fourth-mentioned means being movable relatively to the third-mentioned means, and resilient means carried by the fourth-mentioned 65 means and pressing the third-mentioned means against said other end of the heating rod. 70
